DESIGN FOR A BOOK END

Alexander Leva, New York, N. Y.

Application August 21, 1946, Serial No. 132,696

Term of patent 3½ years

(Cl. D33—1)

To all whom it may concern:

Be it known that I, Alexander Leva, a citizen of the United States of America, residing in city of New York, county of Queens, and State of New York, have invented a new, original, and ornamental Design for a Book End, of which the following is a specification, reference being had to the accompanying drawing, forming part thereof.

The figure on the drawing is a front perspective view of a book end showing my new design. The back is conventionally plain.

I claim:

The ornamental design for a book end, substantially as shown and described.

ALEXANDER LEVA.
